PHOTOCOPY MACHINE

Frank J. Marlow, Sherman Oaks, Calif.
(1808 S. Main St., Los Angeles 15, Calif.)

Filed June 30, 1961, Ser. No. 65,776

Term of patent 7 years

(Cl. D61—1)

FIG. 1 is a front perspective view of a photocopy machine showing my new design;

FIG. 2 is a left side view thereof;

FIG. 3 is a top plan view thereof; and

FIG. 4 is a rear end elevational view thereof.

I claim:

The ornamental design for a photocopy machine, as shown.
